Primary Examiner—Louis S. Zarfas*Assistant Examiner*—Catherine R. Oliver*Attorney, Agent, or Firm*—Young & Basile, P.C.**[57] CLAIM**

The ornamental design for a golf bag divider, as shown and described.

DESCRIPTION

FIG. 1 is a top perspective view of the golf bag divider showing my new design; and.

FIG. 2 is a top plan view thereof, the bottom plan view being identical.

The broken line showing of environment in FIG. 1 is for illustrative purposes only and forms no part of the claimed design.
